UNITED STATES PATENT OFFICE.

EDWIN C. RUTHVEN, OF PHILADELPHIA, PENNSYLVANIA, ASSIGNOR TO
DAVID WOLFE BRUCE, OF NEW YORK, N. Y.

DESIGN FOR A FONT OF PRINTING-TYPE.

SPECIFICATION forming part of Design No. 19,710, dated March 18, 1890.

Application filed January 4, 1890. Serial No. 335,937. Term of patent 14 years.

To all whom it may concern:

Be it known that I, EDWIN C. RUTHVEN, a citizen of the United States, residing at Philadelphia, in the county of Philadelphia and State of Pennsylvania, (assignor to DAVID WOLFE BRUCE,) have invented a new and original Design for a Font of Printing-Type, of which the following is a specification, reference being had to the accompanying typographic impressions, forming part thereof.

These typographic impressions are exact representations of the design, in which are comprised capital letters, punctuation-points, numerals, and the dollar and pound-sterling symbols, and its nature is fully shown therein.

The characteristic features of this design are the wide fields inclosed within a very light line toward the left and upper portions and a very heavy shade line toward the right

and below, said fields being traversed by lines, 20 also very light, beginning at the left and above and extending diagonally downward and toward the right, dividing the fields traversed by alternate lines and narrow spaces.

The punctuation-points, numerals, and the 25 dollar and pound-sterling symbols are all drawn in perfect keeping with the capital letters.

What I claim as my invention, and desire to secure by Letters Patent, is—

The design for a font of printing-types, as herein described, and shown in the accompanying typographic impressions.

EDWIN C. RUTHVEN.
